WAYGUARD AND PLATFORM CONSTRUCTION FOR MACHINE TOOLS

Henry M. Lucas, Cleveland Heights, Ohio, assignor to The Lucas Machine Tool Company, Cleveland, Ohio, a corporation of Ohio

Application June 6, 1931. Serial No. 542,643

20 Claims. (CI. 29—26)

This invention relates to machine tools and has particular reference to machines of the horizontal boring machine type wherein the work is adapted to be fixed to a table movable crosswise of a saddle which in turn is movable along ways of the bed extending longitudinally thereof.

In machines of this type, increasing sizes of work pieces to be machined have required gradual increases in the width of the machine, i. e., in the length of the saddle crosswise of the machine and therefore in the distance between the longitudinally extending ways along which the saddle is adapted to slide. However, as machines of this kind have heretofore been constructed, there is a limit to the extent to which the width can be increased, the width being limited by the requirement that the operator must be able, while standing on the floor on either side of the machine, to reach in and have access to the tool or tools supported by the spindle or boring bar.

The object of the present invention is to provide a construction wherein there is practically no limit imposed on the width which may be given to a machine of this kind, thus making it possible for the machine to accommodate work pieces of greater sizes than heretofore.

In the attainment of the above object, the bed of the machine is lowered so that the ways are nearly at the floor level, and I provide over the ways combined wayguards and a platform which constitute a more or less complete covering for the ways and for the machine bed between the ways, this structure not only protecting the ways against injury from falling objects and the like but being formed of material such that they will readily stand the weight of the operator so that it will be possible for him to step up onto the platform and thus have easy access to the tools, a condition or situation which would be very difficult with unusually wide machines if constructed as heretofore.

The invention may be briefly summarized as consisting in certain novel combinations and arrangements of parts which will be described in the specification and set forth in the appended claims.

In the accompanying drawings,

Figure 1 is a side elevation of a machine of the horizontal boring machine type equipped with my invention;

Fig. 2 is a top plan view of the same with a part in section.

Fig. 3 is an end view looking toward the head end of the machine;

Fig. 4 is a sectional view substantially along the line 4—4 of Fig. 1;

Fig. 5 is an enlarged sectional view, substantially along the line 5—5 of Fig. 1, showing particularly the combined wayguard and platform; 60

Fig. 6 is an enlarged detail sectional view showing particularly the manner of attaching and operating one of certain curtain-like members which are attached to the saddle and are wound up or unwound as the saddle is moved along the ways of the bed, these members closing gaps between the main horizontal guard and platform members which are stationarily mounted. 70

Above I have mentioned the fact that my invention has especial utility with a particular kind of a machine, namely, a machine of the horizontal boring machine type, and in the drawings, the figures of which are briefly described above, I 75 have illustrated such a machine. However, it is not unlikely that my invention has utility in connection with other types of machine tools, and I wish it to be understood that my invention is not necessarily confined to, and in my claims I do not 80 intend to confine my invention to, a machine of this type.

Referring now to the drawings, 10 represents the bed of the machine, the major portion of which is below the floor level indicated at F in 85 Figs. 1, 3 and 4. At one end of the machine is a head column 11 on which is vertically slidably a head 12 carrying a spindle 13 which may drive suitable tools such as a boring bar 14 the outer end of which is adapted to be supported in a 90 block 15 vertically slidably synchronously with the head 12 in an outer support or tail column 16.

The head column is fixed on the bed but the tail column 16 is preferably movable along the bed on the same ways that accommodate the 95 saddle 17 which is movable back and forth between the head column 11 and tail column 16 and carries the work supporting table 18 which is slidable on ways of the saddle extending lengthwise thereof or transversely of the bed 10. I 100 might mention at this point that my invention does not reside in the mechanism for operating any of the parts, such as for moving the head up and down, for rotating the spindle, for shifting the outer support or tail column 16, for moving 105 the saddle lengthwise of the bed or the table transversely of the bed. In a machine of this kind, provision is made for operating or moving these parts by power and many of them by hand, but the major portion of the mechanism has 110

not been shown and none will be referred to as all these parts may be actuated manually or by power in any suitable manner or by any desired mechanism.

- 5 As above stated, the saddle 17 and the tail column 16 are movable along the same ways of the bed. These ways, which are indicated at 19 and are perhaps most clearly shown in Figs. 4 and 5, are located slightly above the floor level 80 F, as clearly shown in Fig. 4. In this instance there are three ways 19, two along the sides of the bed and one at the middle thereof, the intermediate support provided by the middle way 19 being highly desirable in machines of considerable width, it being remembered that with my invention there is practically no limit to which the width of the machine may be extended—at least convenience of operation imposes no limit.
- 10 Coming now to the parts more directly involving the invention, in order that the operator may have convenient access to the tools located at or near the center line of the machine, I provide a combined wayguard construction and platform on which he can step and in fact upon which he can walk entirely across the machine, for, in accordance with the preferred form of the invention it extends across the machine from substantially one side of the bed to the other, regardless of the width of the latter. This combined wayguard construction and platform includes in this instance three stationary horizontal guard and platform members 20, 21 and 22 preferably formed of very heavy gauge 85 flat rolled steel. The gauge of the steel is preferably such that the platform members are substantially rigid and will not flex under the weight of an operator, and the gauge may vary slightly for different machines depending upon the distance between the points at which it is supported. The members 20 and 21 are in this instance wider than the member 22 and they extend from substantially the sides of the bed inwardly toward the center, and the member 22 is somewhat 90 above the former and covers or closes the gap between them, note particularly Figs. 4 and 5. Vertically they are located somewhat above the three ways 19 (Fig. 4) the middle member 22 being somewhat further from the middle way 19 in order that there may be sufficient metal between it and the way 19 to accommodate one 95 of the operating screws or shafts.
- 15 As before stated, these guard and platform members are stationary. At their forward ends they are supported on the base of the head column 11 and at their rear ends they are supported on a so-called shaft support 23 which is located in stationary position at the rear end of the bed 10. The guard and platform members may be supported on the base of the column 11 and on the shaft support 23 in any suitable way but preferably they rest upon and are secured to suitable attaching supports, such as angles 24 (see particularly Fig. 5). These guard and platform members pass freely through the saddle 17 and outer support or tail column 16 and preferably they are supported thereby, that is to say, the saddle and base of the outer support or tail column have horizontal slots (note Figs. 1 and 4) 100 through which the members 20, 21 and 22 extend, with the latter resting on the lower walls forming the slots. As a result of supporting these guards and platform members intermediate their ends on the saddle and tail column the distance between points of support is reduced and a lighter

gauge steel may be employed, but it is to be understood that in all instances a sufficiently heavy steel must be used to prevent bending under the weight of the operator as he steps up onto the platform. I may, if desired, secure to the lower side of the saddle the equivalent of steps 25 which can be conveniently formed by attaching a plate to the under side of the saddle where it projects laterally beyond the front side of the bed a channel member 25^a (note Fig. 3). I do not regard 85 these steps as necessary, but they are rather convenient and make it easier for the operator to pass over the machine across the platform as the distances from the floor to these steps and from the steps to the front guard and platform member 20 and from the latter to the middle guard and platform member 22 are substantially uniform.

Inasmuch as the guard and platform members 20, 21 and 22 span the distance and cover the space between the outer sides of the bed, it is obvious that the ways 19 of the bed are protected by these members alone against articles falling upon them, but I wish to protect them further against chips and the like lodging on the surfaces of the ways, and therefore I cover the vertical openings where necessary between the guard and platform members 20 and 21 and the bed and between the upper central guard and platform member 22 and the adjacent edges 100 of the guard and platform members 20 and 21 beneath. I prefer to accomplish this by flexible strips 26 which are wound onto or unwound from spring drums 27 and at their outer free ends are attached at 28 to the saddle. These strips may 105 be formed of flexible metal, such as copper or brass, and at their edges extend into grooves formed in the guard members and bed, as clearly shown in Fig. 5. In all, I prefer to employ six of these drums and flexible strips (note Fig. 2), 110 four being located between the saddle and the head of the machine and two being located between the saddle and the rear end of the machine. The springs drums for the four strips which are located between the saddle and the head of the 115 machine are supported on the bed and the flexible strips are attached to the saddle in a manner such as to fill the vertical spaces between the outer portions of the guard and platform members 20 and 21 and the bed and the vertical spaces 120 between the outer portions of the upper central guard and platform member 22 and the inner portions of the members 20 and 21 beneath, the edges of the strips running into the grooves of the upper and lower members, as previously described. The drums for the other two flexible strips which extend from the saddle to the rear end of the machine are supported on the shaft support 23 (note Fig. 2) and they are attached to the saddle so as to cover the vertical spaces 125 between the upper central guard and platform member 22 and the guard and platform members 20 and 21. Rearwardly of the saddle the outer vertical spaces between the guard and platform members 20 and 21 and the bed are not closed as 130 it is not thought that closure of these spaces is necessary. The arrangement is such that as the saddle is moved inwardly the four forward drums wind in the strips while the two rear drums pay out the strips, and when the saddle is moved rearwardly, the reverse action takes place.

135 From the above it will be seen that I have provided a very practical construction wherein the width of the horizontal boring mill and similar types of machines can be extended a great

deal farther than has heretofore been possible or feasible from a practical standpoint by an arrangement such that an operator can walk up onto the machine over the ways without injuring them in order to obtain access to the tools, thus providing a structure having the double function of a platform and guards for the ways, the ways being protected not only from injury by the feet of the operator in walking up onto and across the bed but also from falling objects.

While I have shown the preferred construction, I do not desire to be confined to the precise details but aim in my claims to cover all modifications which do not involve a departure from the spirit and scope of the invention and also to various applications of my invention to different kinds of machine tools as long as the construction is such that my invention in its present form or more or less obviously modified may be applied thereto.

Having thus described my invention, I claim:

1. A machine tool having a bed with ways, a member slidably supported on said ways, combined guard and platform members extending over the bed so as to substantially cover it, said combined guard and platform members adapted to support an operative and protect a plurality of said ways and the bed therebetween being stationary and extending through and in supporting relation with said sliding member.

2. In a machine tool, a bed having ways for a sliding member, a wayguard and platform construction comprising plates extending substantially horizontally over the bed, and upright strips between the plates and the bed, the ends of said strips being attached to the slidable member.

3. A machine tool having a bed with ways for one or more sliding members, a wayguard and platform construction comprising plates extending over the bed and including a central plate above two outer plates, and upright strips closing the vertical spaces between the central plate and the outer plates.

4. A machine tool having a bed with ways for one or more sliding members, a wayguard and platform construction comprising plates extending over the bed and including a central plate above two outer plates, and upright strips closing the vertical spaces between the central plate and the outer plates, said strips at their ends being attached to one of the sliding members.

5. In a machine tool, a bed having ways for a sliding member, a combined wayguard and platform construction comprising horizontal stationary plates extending over the bed, and spring drums carrying vertical strips attached to the sliding member and serving to close the vertical spaces against entrance of foreign particles.

6. In a machine tool, a bed having ways for a sliding member, a combined guard and platform construction including stationary plates attached at their ends to head and tail portions of the machine and passing through the sliding member, and drums located at the head and tail portions of the machine having strips the ends of which extend to and are attached to the sliding member, said strips serving as closures for vertical spaces between the plates and the bed or between the plates themselves.

7. In a machine tool, a bed having outer ways and an inner way, a slidable member movable along said ways, wayguards extending over all said ways and through said slidable member, the

guard for the inner way being above and projecting over the guards for the outer ways.

8. A machine tool comprising a frame member, a plurality of ways on said frame member, a movable member supported on said ways, and platform means supported by one of said members and projecting over said ways spaced therefrom and adapted to support an operative.

9. A machine tool comprising a frame member, a plurality of longitudinal ways on said frame member, a movable member supported on said ways, and platform means supported by one of said members and projecting into the other of said members and adapted to support an operative.

10. A machine tool comprising a frame member, a plurality of longitudinal ways on said frame member, a movable member supported on said ways, and platform means formed of substantially rigid material supported by one of said members and extending through the other of said members and adapted to support an operative.

11. A machine tool comprising a frame member, a plurality of longitudinal ways on said frame member, a movable member supported on said ways, and platform means supported by said members adapted to support an operative.

12. A machine tool comprising a frame member, a plurality of longitudinal ways on said frame member, a movable member supported on said ways, and platform means approximately the width of said bed member supported by one of said members and adapted to support an operative.

13. A machine tool comprising a bed member, a plurality of longitudinal ways on said bed member, a movable member supported on said ways, and platform means approximately the width of said bed member supported by one of said members and extending through the other of said members adapted to support an operative.

14. A machine tool comprising a frame member, a plurality of horizontally spaced ways on said frame member, a movable member supported on said ways, and guard means adapted to protect a plurality of said ways and said frame therebetween supported by one of said members, said guard means projecting over said ways spaced therefrom and embracing a plurality of said ways and said frame therebetween.

15. A machine tool comprising a frame member, a plurality of horizontally spaced ways on said frame member, a movable member supported on said ways, and guard means adapted to protect a plurality of said ways and said frame member therebetween supported by one of said members, said guard means projecting over said ways and extending through the other of said members and embracing a plurality of said ways and said frame member therebetween.

16. A machine tool comprising a bed, a plurality of ways on said bed, a member supported on said ways, a guard above said ways and supported by said bed, and a flexible member between said guard and said bed.

17. A machine tool comprising a bed, a plurality of ways on said bed, a member supported on said ways, guard means above said ways supported by said bed and extending through said member, and guard means between said first mentioned guard means and said bed, one end of said second mentioned guard means being connected to said movable member.

18. A machine tool comprising a frame member, a plurality of longitudinal ways on said frame member, a movable member supported on said ways, a plurality of overlapping guards supported by one of said members above said ways and projecting into the other of said members, one of said guards being located above the other.
19. A machine tool comprising a frame, a horizontal bed member forming a part of said frame, a plurality of spaced longitudinal ways on said bed member, a movable member supported on said ways, a plurality of spaced guards above said ways, said guards being supported by one of said members and projecting into the other of said members, and a center guard supported by one of

said members and projecting into the other of said members, said center guard extending from one of said spaced guards to the other and offset therefrom.

20. A machine tool comprising a frame, a horizontal bed member forming a part of said frame, a plurality of spaced longitudinal ways on said bed member including a third way located between two outside ways, a movable member supported on said ways, way guards over said ways supported by one of said members and projecting into the other of said members, the wayguard over said third way projecting over the wayguards over said outside ways and spaced thereabove.
